DESIGN FOR A COMPUTING MACHINE

Walter A. Anderson, Bridgeport, Conn., assignor
to Underwood Elliott Fisher Company, New
York, N. Y., a corporation of Delaware

Application November 30, 1939, Serial No. 88,593

Term of patent 14 years

To all whom it may concern:

Be it known that I, Walter A. Anderson, a citizen of the United States, residing at Bridgeport, in the county of Fairfield and State of Connecticut, have invented a new, original, and ornamental Design for a Computing Machine, of which the following is a specification, reference being had to the accompanying drawings, forming part thereof.

Figure 1 is a perspective view of a computing machine, showing my new design.

Figure 2 is a back view thereof.

I claim:

The ornamental design for a computing machine, as shown.

WALTER A. ANDERSON.
